LOCK NUT

Rudolph Funk, Warminster, Pa.

Application April 28, 1944, Serial No. 533,215

6 Claims. (Cl. 151—21)

1

This invention relates to lock nuts and more particularly to an improved nut of a self-locking character and embodied in a novel and unique, unitary or self-contained structure which is capable of self-retention when placed in use on a bolt, screw or other like-threaded element.

The prime object is to produce a simple yet practical and highly efficient, self-retentive nut which is readily applied in use; can be placed in any desired position lengthwise of the bolt, screw or other threaded element and not necessarily tight against the piece of work nor aided by an additional, separate locking nut or element; and is removable and re-usable at will, without loss in its self-retentive qualities and effectiveness.

The invention consists structurally in the provision of a nut having a rigid main body portion, bored and threaded to fit (substantially in the usual way) the correspondingly threaded portion of the bolt, screw or other element for which it is intended to be applied in use. This nut has a normally contracted, integral portion which either is inherently resilient in itself or else confinedly surrounded and supplemented by a separate resilient member in close cooperative association therewith. The bore of this inherently resilient or resiliently-confined portion is substantially in continuity of the bore in the main body portion and correspondingly threaded but at least slightly contracted whereby this body portion expands and reacts to engage the bolt or other threaded element clampingly like a brake band and thus holds the applied nut in place thereon.

Specific but non-limiting practical examples of the nut of the present invention are set forth with particularity in the following description in conjunction with the accompanying illustrative drawings, in which:

Fig. 1 is an elevational and partially sectional view illustrating the application of the nut in one of its forms to a bolt placed in a piece of work;

Fig. 2 is a fragmentary, sectional view on the line 2—2 of Fig. 1;

Fig. 3 is a top plan view of the nut alone;

Fig. 4 is a section on the line 4—4 of Fig. 3;

Figs. 5, 6 and 7 are sectional detail views illustrating the stages in the forming of the nut; Fig. 5 showing the nut body proper as originally formed with a straight cylindrical, screw-threaded bore; Fig. 6 showing the reduced upper portion of the body as contracted for the

2

purposes of the invention; and Fig. 7 showing how the contracted upper portion of the body may be slotted;

Fig. 8 is a partial side elevational and sectional view of the supplemental resilient ring member for the nut in the form thereof as illustrated in Figs. 1 to 4, inclusive;

Fig. 9 is a top plan view of the resilient ring member of Figs. 1 to 4, inclusive;

Fig. 10 is a top plan view of a modified form of nut body proper;

Fig. 11 is a side elevation of the nut body shown in Fig. 10;

Fig. 12 is a side elevation of the complete nut with the resilient ring member attached to the modification of the body portion proper shown in Figs. 10 and 11;

Fig. 13 is a top plan view of another modification of the nut structure;

Fig. 14 is a side elevation of the nut shown in Fig. 13;

Fig. 15 is a section on the line 15—15 of Fig. 13;

Fig. 16 is a sectional view of a further modification of the nut structure;

Fig. 17 is a side elevation of the nut shown in Fig. 16;

Fig. 18 is a sectional view of a modification of the nut structure shown in Fig. 16;

Fig. 19 is a sectional view of a welded two-piece structural modification;

Fig. 20 is a sectional view, illustrative of the original formation of an integral single-piece nut structure;

Fig. 21 is a sectional view, illustrative of the procedure in finishing the nut from the pre-formed body shown in Fig. 20;

Fig. 22 is a view in partial side elevation and section of the nut as produced according to the procedure illustrated in Figs. 20 and 21;

Figs. 23 and 24 are sectional views illustrative of the original and the final stages in the formation of a modification in a single-piece nut structure;

Fig. 25 is a partial side elevation and section of the nut completed in accordance with the procedure illustrated in Figs. 23 and 24;

Figs. 26, 27 and 28 are illustrative of the adaptation of the locking nut of the present invention in an anchor-plate type of construction; and

Fig. 29 is a view showing how an anchor-plate type of construction in accordance with the present invention may be applied with a bolt to a piece of work.

Referring now to the drawings in detail, and first more particularly to Figs. 1 to 15, inclusive, the numerals 32 and 33 (see Figs. 1 and 2) designate, respectively, two pieces of work joined together by an ordinary bolt 34 in a conventional manner except as to the use of a locking nut of the present invention for the fastening thereof. The applied nut of the present invention is designated generally by the numeral 35.

The nut is characterized by its peculiarly unique structural form and arrangement and its relative inherent resiliency in a part or parts thereof as hereinafter more specifically described in connection with the various modifications, whereby it clampingly engages around the entire circumference of the bolt 34 and is thus self-retentive in resistance to the effect of vibration and other influences which tend to jar and move the ordinary conventional nuts out of place.

The nut of the present invention need not necessarily be set close to the adjacent face of the work piece 32 and thus tightened, but may be located in spaced relation away from the work piece and at any desired place on the threaded portion of the bolt. So, too, the nut of the present invention can be removed from the bolt without injury to either one thereof. Thus, each is re-usable over and over again.

In detail, the nut in the structure shown in Figs. 1 to 4, inclusive, comprises a substantial, solid, main body portion 35 and a reduced and slightly contracted neck portion 36, the neck portion being surrounded and confined by a characteristically resilient collar or ring member 37. That is to say, the main body portion 35 and integral neck portion 36 can be and usually are made of the same metal alloy as the ordinary nut, but the confining collar or ring member 37 is of a particular and inherently resilient character, so that, when fitted about the neck portion 36 in the composite structure, it is yieldable to a limited degree and reactive with a constant tendency to return the neck portion back to its normal, originally contracted set after it has been expanded in the placing of the nut on a bolt or like screw-threaded element in use. The member 37 thus not only functions effectively in the clamping of the nut retentively on the bolt or other element to which it is applied in use, but also restores the nut to its normal set when detached from such element after use.

As shown more clearly in Figs. 8 and 9, the collar or ring member 37 is in the form of a cupped or annularly flanged ring. The inwardly flanged portion 38, surrounding the central opening 39 of this member 37, is fitted tightly about the outer end portion 46 of the restricted neck 36, and with its larger edge portion 40 held in annular engagement with the adjacent main body portion 35 of the nut (see Figs. 2, 4 and 15). Also, the top inner surface of the cup 37 is pressed tightly over the outside diameter of an annular shoulder 44 formed on the neck 36 of the nut proper just below the said end portion 46.

In the particular structure illustrated in Figs. 2 and 4, the inwardly flanged portion 38 of this confining collar or ring 37 is held in an annular groove formed in the adjacent neck portion by a procedure to be described herein more fully in detail. In this structural form of the nut the larger edge portion 40 of the collar or ring member is fitted inwardly behind an upstanding annular bead or shoulder 41 formed marginally on

the adjacent base or main body portion 35 of the nut.

In Fig. 15 the general structure is substantially the same as that of Figs. 2 and 4 except that, instead of the edge portion 40 of the collar or ring member being fitted inwardly of a marginal bead or shoulder, as at 41, it is fitted outside an annular shoulder 42 which is formed on the base or main body portion 35 some distance inwardly from the margin thereof.

In producing the integral base or main body portion 35 and reduced neck portion 36 for all of the herein described nut structures the procedure is the same, except as to the provision for the attachment thereto of the resilient element which confines and cooperatively affects the functional action of the neck portion 36 in the self-retentive quality of the nut. The first step in the procedure is to form the body portion proper substantially as shown in Fig. 5, with a continuous, straight, cylindrical bore 43, screw-threaded throughout the entire length thereof and corresponding to the threading of the bolt or the like to which the nut is to be applied in use. The neck portion 36 is then compressed and squeezed inwardly, all around, whereby to deform and contract it slightly as indicated in Fig. 6 and give a tapered restriction to that part of the screw-threaded bore 43 which is located in the neck portion.

An external annular shoulder 44 is formed on the neck portion 36 of the nut body proper adjacent its outer end and the outer end portion of the neck is counterbored, as at 45, thereby producing an upstanding annular flange 46 in proximity to said annular shoulder 44.

The external diameter of the flange 46 corresponds to the diameter of the inwardly flanged opening 39 of the collar or ring member 37, which latter member is slipped over the thus formed and contracted end portion of the neck 36, with its internal annular flange 38 resting on the shoulder 44 and fitted tight around the upstanding flange 46. As thus placed, the lower annular edge portion 40 of the collar or ring member 37 is fitted snugly behind the annular bead or shoulder 41 on the base or main body portion 35 of the nut or else outside the shoulder 42.

After the member 37 is in the said position on the nut body proper the upstanding flange 46 is spun or otherwise turned outwardly and down tightly upon the inturned flange 38, thereby producing, in effect, an external annular groove 47 in which said flange 38 is held securely (see Figs. 2 and 4).

In Fig. 15, the same general structural scheme is carried out, i. e., as to the form and arrangement of the body portion proper and the mounting of the collar or ring member 37 thereon, except as to the lower annular edge portion 40 of said member 37, which latter, in this particular modification, is fitted tightly around the outside of an annular shoulder 42 formed on the base or main body portion 35 of the nut instead of inside of the marginal bead or shoulder 41 as shown in Figs. 2 and 4.

In applying the nut of the present invention to a correspondingly threaded bolt 34 or the like, in use, the normally contracted, tapered neck portion 36 containing the restricted upper part of the threaded bore 43 is forcibly expanded. At the same time the confining collar or ring member 37 is correspondingly expanded and is then constantly reactive and tending to urge the thus expanded neck portion 36 back to its normal

set, whereby the nut is clamped tightly on the bolt 34 or other like screw-threaded element, and, without extraneous assistance, is thus effectively self-resistant to vibration and shock which might cause movement and displacement of an ordinary conventional nut not jammed tight against an adjacent piece of work or else held in place by a separate jam nut tightened thereagainst.

It is here particularly stressed that the nut of the present invention, in some of its practical uses, need not be necessarily tightened against a piece of work but may be spaced some distance apart therefrom, and yet it is self-retentive in whatever position it is placed on the bolt or the like to which it is applied in use. Not only this, but it can be readily removed, at will, without injury to itself or the screw-threaded element on which it is applied; and, because of the inherent resiliency created by its peculiarly characteristic make-up, whereby it recovers its normal set, it can be used over and over again with effect substantially equal to that of its first use.

While in some structures the inherent though limited yieldability of the reduced neck portion 36 of the nut body proper permits of ample expansion for the purposes of the invention and said neck portion can be left solid and unbroken throughout its entire extent, it may be more practical and satisfactory to cut it lengthwise at one or more places to enhance its contractibility and expansibility, particularly in adaptations of the invention where the supplemental resilient collar or ring member 37 is provided in a composite structure. Thus, as shown in Figs. 3 and 7, the neck portion 36 may have an open-ended slot 48 cut or otherwise formed therein; or, as shown in Figs. 10 and 11, two of such slots may be provided in diametrically opposite relation to each other. A larger number of these slots may be provided in some structures, depending principally on the size of the nut and the particular use for which it is intended; but, in the more common and general use of the nuts of the present invention, either the single or double slotted provisions and arrangements will suffice.

The structures illustrated in Figs. 1 to 15, inclusive, are substantially alike except as to the particular fitting of the lower annular edge portion of the confining collar or ring member 37 to the base or main body portion 35 of the nut, and in the number of slots 48 in the reduced neck portion 36. As to the provision of said slots 48 it is here noted that the same can be cut in the neck portion 36 either before the compressing and contracting of this part, but preferably after the screw-threading of the bore 46 and not until the nut body proper has reached the contracted stage shown in Figs. 6 and 7 in the process of manufacture.

In Figs. 16, 17 and 18, the nut body proper is substantially the same in general structural form as those above described. The resilient confining collar or ring member, however, is in a modified form, in that it is cupped in an integral formation providing a crowned portion 49 which covers and encloses the upper open end of the nut body proper and is spaced a sufficient distance therefrom to afford ample clearance for the protruding end of the bolt or like element to which the nut is applied, as, for example, in an instance approximately like that illustrated in Fig. 1, where the applied nut is adjacent the end of the bolt.

In the particular form shown in Fig. 16 the collar portion proper 37 has an internal annular flange 50 that is fitted snugly around the upstanding top flange 46 of the neck portion 36 and rests on the lateral annular shoulder 44. The lower skirt portion of the collar 37 as thus fitted on the neck portion 36 is afterwards crimped inwardly, forming an internal, annular bead 51 in tight engagement under the shoulder 44, thereby holding the collar 37 securely in place. The function of this particular collar member is primarily for the same purpose as those in the herein previously described structures, but, in addition, affords a protective covering at the outer end of the nut.

In this modification shown in Fig. 16 the annular top face of the base or main body portion of the nut is plain and flat throughout and the lower edge portion of the collar or ring member 37 just touches the adjacent face of the nut body, and the only means of attachment of said member 37 is the aforesaid fitting of the internal flange 50 on the reduced neck portion of the nut body, together with the annular, inward crimping of the skirt portion of said member 37 under the annular shoulder 44 on the neck portion 36.

In Fig. 18 the collar member 37 is made in two pieces, fitted one within the other. The inner piece 52 is flanged inwardly and fitted to the neck portion 36 of the nut body substantially as in the modifications illustrated in Figs. 1 to 15, inclusive, and the lower edge portion of the piece 52 is fitted inside the marginal bead or shoulder 41 of the base or main body portion of the nut substantially as shown in Figs. 2 and 4. The outer piece 53 of this two-piece collar 37 is formed substantially the same as the single-piece collar in Fig. 16, i. e., it has the crowned cover portion 49, but is without the internal annular flange 50, it being plain surfaced interiorly so as to fit telescopically over the inner piece 52.

The two pieces 52, 53, of the collar member, as fitted together, are both crimped inwardly as at 54, and engaged retentively under the annular shoulder 44 of the neck portion 36 of the nut body in a manner substantially the same as for the single-piece member shown in Fig. 16. In this two-piece collar structure the lower annular edge portion of the outer piece 53 just touches the top of the annular marginal bead or shoulder 41 of the base or main body portion of the nut.

A further structural modification is illustrated in Fig. 19. This structure, in general, is quite similar to those previously described, and also except as to the manner in which the flanged collar member 37 is attached to the body portion proper of the nut. In this particular modification, the inward, annularly flanged upper end portion of the collar member 37 is fitted on the adjacent end portion of the neck part 36 of the nut body substantially as in the previously described structures, but the lower edge portion of the collar member 37 is welded, as at 57, to the annular top face of the base portion of the nut body proper.

While the herein described multiple-piece structures may be the more desirable and practical in the manufacture of the nut of the present invention because of certain advantages in the procedure incidental thereto, the nut can be made in an integral one-piece structure and is so contemplated, and exemplification thereof is illustrated in Figs. 20 to 25, inclusive. There are two separate illustrations of such a structure, specifically different in details of the procedure in form-

ing the nut, but substantially alike in the finished form thereof.

Referring first to Figs. 20, 21 and 22, it is noted that the nut comprises an integral one-piece body 58, the major part of which is formed substantially the same as in all of the previously described structures. In this particular modification, an annular flange 59 is formed on the outer end of the neck portion 36 of the nut body proper, and after the screw-threading of the bore 43 and contraction of the neck portion 36 is accomplished, the flange 59 is then turned downward in annularly spaced relation about the neck portion and with its marginal portion 60 close to or in contact with the top face of the base portion of nut body proper, as indicated by dotted lines in Fig. 21 and in full lines in the completed structure as shown in Fig. 22.

The edge portion 60 of the downturned flange 59 may be left free of any fixed attachment to the base portion of the nut body proper 35; or, if desired, it may be welded or otherwise securely fastened to the nut body proper.

The structural procedure is different in Figs. 23, 24 and 25. In this modification, instead of forming the flange 59 on the neck portion 36, an upstanding, annular, collarlike flange 61 is formed on the base portion 35 of the nut body proper in spaced relation to the neck portion 36. This flange 61 is afterwards turned inwardly until its upper edge portion is brought close to or in contact with the adjacent end portion of the neck 36 (see, Figs. 24 and 25) and either left free of fixed attachment or welded or otherwise fastened securely to the neck portion, as may be desired. The finished form and effect of this modification in Fig. 25 is substantially the same as that in Fig. 22.

In both of the modifications just above described, if the metal or material of which the nut is constructed does not naturally possess ample inherent resiliency for the purposes of the present invention, either the normally contracted neck portion or its surrounding and confining companion member (or both thereof) can be specially treated and tempered to give the requisite resiliency thereto. So, too, it is here expressly stated that either the neck portion 36 or its outer cooperative member (or both) may be slotted equivalently to the hereinbefore described slotting of the parts, or else left integrally solid, accordingly as may be desired.

In Figs. 26 to 29, inclusive, are illustrated adaptations of the self-retentive characterization of the nut of the present invention to the anchor-plate type of nut, the only specific difference in structure from that of the ordinary conventional nut of said type being in the nut body portion proper and possibly the manner in which the anchor-plate member is attached to the same. In this adaptation of the invention, as illustrated, the nut part proper is, specifically, that shown in Fig. 15. However, it may be of any of the other specific forms herein previously described.

In Fig. 27 the anchor-plate member 62 is shown as being made as a separate piece and having a central opening whereby it is fitted to the lower end portion of the nut part proper as indicated conventionally at 62A.

In Fig. 28 the anchor-plate member 62 is shown as an integral extension of the nut part proper in a one-piece structure.

In both of the illustrated modifications of the anchor-plate type of nut, the plate members

62 are apertured near their opposite ends, as at 63, for the reception of rivets or the like to fasten the plate member to a work piece in the regular conventional manner. A nut of this kind is shown in Fig. 29 as applied to a bolt 34 in conventional pieces of work 64, 65, with its plate member 62 riveted, as at 66, to the work piece 64.

I claim:

1. A self-retentive nut, comprising a body having, therethrough, a bore which is screw-threaded throughout its working length, a portion of the bore being located within a non-deformable and form-retentive part of the nut body, another part of the nut body being deformable but resiliently influenced so as to be urged constantly to recovery of its normal form, in which form it is contracted and the portion of the nut bore located therein is incidentally constricted to an appreciable degree, whereby, when the nut is placed on the bolt or other element, said contracted part of the nut body is expanded but is reactive to create and maintain a self-retentive clamping effect of the nut upon the bolt or other element to which it is applied around the circumference thereof, and a resilient member confining said contracted part of the nut body and reacting to return this nut body part to its normal form, said resilient member having an intermediate portion spaced from said nut body.

2. A self-retentive nut, comprising a body having, therethrough, a bore which is screw-threaded throughout its working length, the normal major part of the nut body being substantially rigid, non-deformable and form-retentive in its use, a reduced other part of the nut body being deformable but resiliently influenced so as to be urged constantly to recovery of its normal form, in which form said reduced portion is contracted to an appreciable degree and the portion of the nut bore located therein is thereby correspondingly constricted, so that, when the nut is placed on the bolt or other element, said reduced part is expanded but is reactive to create and maintain a substantial clamping effect upon the bolt or other element sufficient to hold the placed nut from displacement that might result due to vibration or shock, and an inherently resilient collar member cooperatively surrounding and confining said reduced portion of the nut body and expanding therewith but reacting to return this nut body portion to its normal form, said collar member having ends arranged in contact with said nut body, said supplemental member being spaced from said nut body intermediate said ends.

3. A self-retentive nut of the character described, the same comprising an integral nut body proper, the major part of which is rigid, non-deformable and form-retentive and the lesser other part thereof being deformable and expandable, reduced in size and of circular cross-section, said reduced part being normally contracted and in a tapered form, the body having a bore extending through both of said specified parts and screw-threaded throughout its entire working length, the portion of the bore within the major body portion of the nut being of a straight, cylindrical, form and size to fit, in the ordinary way, the bolt or similar element on which the nut is placed, and that portion of the bore within said reduced and contracted lesser body part being constricted appreciably and tapered correspondingly to the taper of said lesser body part, whereby, when the nut is placed on the bolt or other element, this part of the body proper is expanded, and an inherently resilient collar member coop-

eratively surrounding and confining said normally contracted lesser part of the nut body proper and expanding therewith but reacting constantly to return this nut body part back to its normal form, said surrounding and confining collar member being capped and flanged and at least a part thereof being fixedly attached to an adjacent part of the nut body proper.

4. A self-retentive nut of the character described, comprising a rigid, non-deformable and form-retentive major body portion proper, bored and conventionally screw-threaded, an integral lesser body portion being deformable and expansible, reduced in size and normally contracted, and bored in continuation of the bore of said major body portion and with like screw-threading, but appreciably constricted substantially correspondingly to the contraction of said lesser body portion, said lesser body portion being inherently resilient to permit limited expansion thereof when the nut is placed on the bolt or similar element and is reactive constantly to self-recovery of its normally contracted form, and said lesser body portion being supplemented in its function and effect by a separately formed but integral part of the nut body in a one-piece structure as distinguished from a multiple-piece composite structure, the said supplemented part being formed into a partly spaced, though integral collar surrounding said lesser body portion and affording a support between the same and said major body portion of the nut.

5. A self-retentive nut of the character described, comprising a rigid, non-deformable and form-retentive major body portion proper, bored and conventionally screw-threaded, an integral lesser body portion being deformable and expansible, reduced in size and normally contracted,

and bored in continuation of the bore of said major body portion and with like screw-threading, but appreciably constricted substantially correspondingly to the contraction of said lesser body portion, said lesser body portion being inherently resilient to permit limited expansion thereof when the nut is placed on the bolt or similar element and is reactive constantly to self-recovery of its normally contracted form, and said lesser body portion being formed with an integral circular outer flange at its upper end, said flange being turned down in spaced relation around said reduced and contracted body portion and with its margin in supported engagement with the major body portion proper of the nut.

6. A self-retentive nut of the character described, comprising a rigid, non-deformable and form-retentive major body portion proper, bored and conventionally screw-threaded, an integral lesser body portion being deformable and expansible, reduced in size and normally contracted, and bored in continuation of the bore of said major body portion and with like screw-threading, but appreciably constricted substantially correspondingly to the contraction of said lesser body portion, said lesser body portion being inherently resilient to permit limited expansion thereof when the nut is placed on the bolt or similar element and is reactive constantly to self-recovery of its normally contracted form, said major body portion of the nut being formed with an upstanding annular collar-like flange surrounding and spaced from the lesser body portion and with its upper margin turned inward into supported contact throughout with the adjacent upper end of said lesser body portion.

RUDOLPH FUNK.
